(57) **CLAIM**

The ornamental design for a capsule for washing products, as shown and described.

DESCRIPTION

FIG. 1 is a bottom perspective view of a capsule for washing products of the present invention;

FIG. 2 is a top perspective view of the capsule for washing products of FIG. 1;

FIG. 3 is a front view of the capsule for washing products of FIG. 1;

FIG. 4 is a back view of the capsule for washing products of FIG. 1;

FIG. 5 is a side view of the capsule for washing products of FIG. 1;

FIG. 6 is the other side view of the capsule for washing products of FIG. 1; and,

FIG. 7 is a bottom view of the capsule for washing products of FIG. 1.
